UNITED STATES PATENT OFFICE.

WALTER K. FREEMAN, OF FORT WAYNE, INDIANA.

INDUCTION-MACHINE.

SPECIFICATION forming part of Letters Patent No. 554,670, dated February 18, 1896.

Application filed July 5, 1895. Serial No. 555,054. (No model.)

To all whom it may concern:

Be it known that I, WALTER K. FREEMAN, of Fort Wayne, in the county of Allen, State of Indiana, have invented certain new and useful Improvements in Induction-Machines; and I do hereby declare the following to be a full, clear, and exact description of the same, reference being had to the accompanying drawings, forming a part of this specification,

10 and to the letters of reference marked thereon.

This invention relates to improvements in current-generators and motors, the improvements being more especially applicable to consequent-pole machines, and hence a machine

15 of this character has been illustrated.

The invention resides in certain novel details of construction and combinations and arrangements of parts whereby a compact structure is produced in which a magnetic circuit is secured with a minimum air-gap between the field and armature-core, the lines of force finding a path of minimum resistance, thereby preventing excessive heating and permitting the machine to run loaded to any

25 point within the limit of its capacity.

Referring to the accompanying drawings, Figure 1 is an end elevation of a machine constructed in accordance with this invention. Fig. 2 is an elevation taken at right angles to

30 Fig. 1 with one of the movable sections of the field swung back. Fig. 3 is a top plan view of the frame. Figs. 4 and 5 are vertical sectional views of the frame, taken at right angles to each other.

35 Like letters of reference in the several figures indicate the same parts.

The main frame of the machine is preferably made in an integral casting embodying the base A and the two cheek-pieces or uprights B, between which the pole-pieces of the field are located, together with the body of the armature, as will presently appear.

One of the poles C, a consequent pole, is usually formed integral with the base, centrally between the cheek-pieces, and at the ends between the cheek-pieces there are formed seats D for the ends of movable field-sections E, which latter fit quite accurately between the cheek-pieces and are normally

50 clamped in such position by bolts e passing in through the edges of the said cheek-pieces.

The movable field-pieces E are angular,

both together forming a complete bridge, the line of division between them preferably being centrally of the upper consequent pole F. 55 In other words this upper pole is formed half on one field-piece and half on the other. The main or prime pole-pieces G, around which the field-coils G² are placed, project from the inner faces of the upright portions of the field-pieces at diametrically-opposite points. 60

Clamping-bolts E', at the lower ends of the movable field-pieces, are adapted to form pivots on which the field-pieces may be turned out to the position shown on the left in Fig. 65 2, thus opening the machine for inspection or repairs and permitting the convenient removal or renewal of the field-coils. When the field-pieces are turned back, as indicated, the whole armature is exposed between the 70 cheek-pieces, and, if desired, may be removed in the ordinary manner—i. e., by releasing its shaft from the bearings, one of which, K, is mounted on one of the cheek-pieces and the other of which is on a standard L on the base, 75 sufficiently removed from the cheek-pieces to allow for the location of a commutator M next to the body of the machine.

The commutator-brushes N are preferably supported by the bearing-standard; but the 80 form of brush employed is inconsequential, and hence no particular description of the same is necessary.

To facilitate the insertion and removal of the armature, as well as to secure a more 85 perfect concentration of the lines of force, the cheek-pieces are formed with circular openings Q of a size to allow the armature to pass therethrough, and the bearing K may be supported by a plate or casting K', bolted 90 to the face of the cheek-piece by bolts k, as shown in Fig. 1.

By this construction it will be seen that the armature and fields are entirely inclosed by a magnetic armor, as it were, and the lines 95 of force find the best possible path between the poles, and by making the structure rigid the armature may be run very close to the pole-pieces without danger, thereby securing a short air-gap, the resistance of which 100 is very slight as compared with machines of ordinary construction.

Having thus described my invention, what I claim as new is—

1. In an induction-machine the combination with the base and the cheek-pieces projecting upwardly therefrom, of the movable field-pieces secured between said cheek-pieces 5 and the armature journaled between the movable field-pieces; substantially as described.

2. In an induction-machine the combination with the base, the cheek-pieces projecting upwardly therefrom and having openings 10 therein for the armature-shaft, of the movable field-pieces clamped between said cheek-pieces, and the armature arranged transversely of the cheek-pieces and between the movable field-pieces; substantially as de- 15 scribed.

3. In a consequent-pole induction-machine, the combination with the base having the cheek-pieces projecting upwardly therefrom of the oppositely - arranged movable field- 20 pieces clamped between the cheek-pieces and inclosing the space for the armature, the pole-pieces and cores projecting from the bodies of said field-pieces, and the consequent-pole piece formed by a portion of each field-piece; 25 substantially as described.

4. In a consequent-pole induction-machine, the combination with the base having the cheek-pieces projecting upwardly therefrom and a consequent-pole piece on the base, intermediate the cheek-pieces, of the independent field-pieces having the main and top consequent-pole pieces thereon, clamped between the cheek-pieces and surrounding the armature, and the armature arranged transversely 30 of the cheek - pieces; substantially as de- 35 scribed.

5. In a consequent-pole induction-machine,

the combination with the base having the upwardly-projecting cheek-pieces, the pole-piece located centrally between the cheek-pieces, and the seats for the field-pieces at the ends of the cheek-pieces, of the independent field-pieces clamped between the cheek-pieces, seating in said seats and having projections meeting at the center of the 40 machine to form the upper pole-piece, the main pole-pieces projecting from the upright portions of the field-pieces, the coils surrounding the same, and the armature journaled transversely of the cheek-pieces; substan- 45 tially as described.

6. In a consequent-pole induction-machine, the combination with the base having the upwardly-extending cheek-pieces with armature-openings formed therein, the central 55 pole-piece and the seats for the field-pieces all in one casting, of the independent field-pieces seating in said seats and having overhanging portions meeting at the center to form the top consequent pole, the main pole-pieces projecting inward from the upright portions of the field-pieces, the coils surrounding said poles the armature journaled between said poles transversely of the cheek-pieces and the bolts uniting the cheek-pieces 60 and field-pieces at the bottom and adapted to serve as trunnions on which the field-pieces may be swung back; substantially as de- 65 scribed.

WALTER K. FREEMAN.
